DESCRIPTION

FIG. 1 is a front-right-top perspective view of the indoor trainer bike front wheel riser block showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is a front elevational view showing the application thereof, wherein the broken lines show environment which forms no part of the claimed design.
